U.S. Cl. D6—150

FIG. 1 is a front perspective view of a kitchen cabinet showing my new design, with the sliding flexible panel doors thereof closed;

FIG. 2 is a rear perspective view of the kitchen cabinet of FIG. 1; and

FIG. 3 is a view similar to FIG. 1 but showing in an open position the upper of the sliding flexible panel doors.

The slats seen on the front panels in FIGS. 1 and 3 extend across the top of the cabinet.

This application is a division of my application Ser. No. D. 23,005, filed May 5, 1970 and now Design Pat. No. D. 223,840.

I claim:

The ornamental design for a kitchen cabinet, as shown and described.
